UNITED STATES PATENT OFFICE.

CHARLES G. CUSHMAN, OF NEW YORK, N. Y., ASSIGNOR TO INTERNATIONAL PAPER COMPANY, OF NEW YORK, N. Y., A CORPORATION OF NEW YORK.

LUBRICATING DEVICE.

1,181,997.

Specification of Letters Patent.

Patented May 9, 1916.

Application filed October 29, 1915. Serial No. 58,546.

To all whom it may concern:

Be it known that I, CHARLES G. CUSHMAN, a citizen of the United States, residing at New York, in the county of Kings, State 5 of New York, have invented certain new and useful Improvements in Lubricating Devices; and I do hereby declare the following to be a full, clear, and exact description of the invention, such as will enable others 10 skilled in the art to which it appertains to make and use the same.

This invention relates to an improvement in lubricating devices, and while devised particularly for use on the bearings of 15 grinders employed in the paper making industry can be used in other relations, where a constant feeding of oil to a journal is desired, and more particularly where the rotating parts are heavy and frequent inspection 20 of the journal is desirable.

More particularly, the invention relates to that type of lubricating devices in which the oil is fed from an oil receptacle to the journal by means of material through which 25 the oil flows by capillary attraction.

One of the objects of the invention is to provide a device of this character comprising a plurality of oil feeding members extending from the oil receptacle to the journal, and so arranged that the number of 30 active oil feeding members may be readily increased or decreased to regulate the amount of oil supplied to the bearing.

A further object is to provide for convenient 35 inspection of the journal while the machine is in operation to ascertain whether or not it is being properly lubricated, or is becoming cut or grooved by the presence of foreign material in the bearing.

Another feature of the invention is the 40 simplicity of the means for retaining the oil feeding members in position while at the same time permitting the same, either singly or as a group, to be easily and quickly removed from contact with the journal or placed in working position thereon. This 45 retaining means also permits ready withdrawal of the feeding members from the oil receptacle, either for renewal or repair, 50 as occasion may require.

In the accompanying drawings, illustrating one embodiment of the invention—Figure 1 is a sectional view, somewhat diagrammatic, of the lubricating device, this section being taken on the line 1—1 of Fig. 2; and 55 Fig. 2 is a plan view thereof.

In the drawings, the journal 3 is rotatably supported on a bearing 4 of any standard design, the box here shown being but illustrative and in large measure diagrammatic. A cap 5 is removably secured to bearing 4 by bolts 6. Cap 5 is open at the top, as shown, to afford access to the lubricating means and to permit ready inspection of the journal for ascertaining whether it 60 is being properly lubricated and is in other respects in good working condition.

Removably positioned within cap 5, and adjacent the rear wall thereof, is an oil receptacle 7 open at the top and of substantially the same length as the opening in the cap, but of less width than said opening, so that it will overlie a portion of the journal 65 3, as illustrated in Fig. 1. The front wall 8 of the oil receptacle terminates below the 70 top of cap 5, but the rear wall 9 is extended upwardly and is bent back over the edge of the cap to form a supporting hook 10. This construction provides for the ready removal of the receptacle through the top of 75 the cap for purposes of cleaning and repair, or if for any reason it is desirable to inspect the entire surface of the journal thus exposed within the cap.

The oil is fed from receptacle 7 to journal 80 3 by means of a plurality of strips 11 of felt, or other suitable material, through which the oil may flow by capillary attraction. Preferably these strips are formed by cutting into the edge of a sheet of the felt, or 85 like material, and the other or uncut edge of the sheet is secured in the oil receptacle by a lead weight 12 placed thereon or fastened thereto. The free ends of the strips rest on the downwardly moving portion of 90 the journal surface, and convey to it the oil which they carry by capillary attraction out of the oil receptacle. The weight need not be attached to the receptacle and may at any 95 time be lifted out should it become necessary 100

to replace or clean the strip, or gain access to the entire upper half of the journal.

When an inspection of the journal is desired, the ends of some or all of the trailing strips can be lifted to expose the moving metal beneath, and, if it be found that too much oil is being fed to the journal, some of the strips can be lifted and folded back into the oil receptacle and so be out of action. In this way an easy regulation of the oil consumption is made possible. Should it be necessary for any reason to inspect the entire upper surface of the journal, the oil receptacle and its attached strips can be lifted out through the top of cap 5.

The employment of a plurality of oil feeding strips engaging the surface of the journal has several advantages over the use of a single pad extending the entire length of the surface to be lubricated. The amount of oil which is fed to the journal can be regulated without the aid of mechanical clamps or other similar control of capillary action, and if it should be found that one part of the journal is running hotter than the remainder, the number of strips at the hot end may be increased to feed more oil to that particular part without supplying an excess of oil to other parts of the journal. If one of the strips becomes charred or glazed with dirt, it can be folded back or cut off and another strip be put into action to take its place. Furthermore, as each strip is comparatively narrow, and not likely to be deprived of its regular supply of oil, and not liable to wedge against the shaft, there is little danger that it will become charred or burnt. In this respect the present device offers many advantages over any construction wherein a single pad or oiling strip is used. Ordinarily, not all of the strips shown in Fig. 2 will be in action at any one time, and if a half or a third of them are in action, and the others folded back into the oil receptacle, it is of course possible for the operator to look down through the gaps and see whether the journal is running wet or dry, and whether the number of strips should be decreased to save oil, or increased to save wear on the journal and bearing.

What I claim is:

1. The combination of a bearing, a journal therefor substantially the upper half of which is exposed, an oil receptacle positioned near said exposed upper half, a sheet of suitable oil-transporting material having one edge secured within said receptacle under the oil contained therein, and its other edge cut into a plurality of strips adapted to trail on the rotating journal, said oil-transporting material being arranged to carry oil upward over the edge of said oil receptacle and deliver it to the rotating journal, each of the strips being capable of re-

moval from contact with the journal without disturbing the others, thereby to regulate the place and quantity of oil delivered and facilitate inspection of the journal while rotating.

2. In a lubricating device, the combination with a journal to be lubricated, of a bearing therefor, a cap for said bearing having an opening exposing the top part of the journal, an oil receptacle positioned in said opening and removable from said cap to permit inspection of substantially the upper half of the journal and a sheet of felt having one edge dipping into the oil and its other edge cut into a plurality of strips which are adapted to trail on the journal, each of said strips being capable of removal from contact with the journal without disturbing the others.

3. In a lubricating device, the combination with a journal to be lubricated and a bearing therefor, of a cap secured above said bearing and having a longitudinal opening exposing substantially the upper half of said journal, an oil receptacle in said opening and secured to one side of said cap, said receptacle being removable through the top of the cap, and a sheet of oil feeding felt immersed at one edge in the oil of said receptacle and at its other edge cut into a plurality of strips which trail on the receding surface of the journal and are removable therefrom independently of one another to regulate the quantity of oil supplied to the journal.

4. The combination of a journal and bearing therefor, of a cap secured to said bearing and open at the top, an oil receptacle positioned in said opening, and a plurality of oil-carrying members receiving oil from said receptacle and delivering it to said journal, each of said members being removable from contact with the journal independently of the others to thereby regulate the quantity of oil supplied to the journal.

5. The combination with a journal and a bearing therefor, of an oil receptacle positioned above said journal, a weight therein, a plurality of lubricating members held by said weight with one end immersed in the oil of said receptacle and the other end trailing on the journal, said members being independent of one another and capable of being lifted out of contact with the journal without disturbing the other members.

6. The combination with a journal and a bearing therefor, of a cap secured to said bearing and open at the top to expose a large portion of the top of said journal, an oil receptacle suspended in said opening by engagement with one side of the cap, a weight in said receptacle, a strip of suitable oil-transporting material having one edge secured within said receptacle by said

weight, and its other edge cut into a plurality of strips adapted to trail on the rotating journal, said oil-transporting material being arranged to carry oil upward 5 over the edge of said oil receptacle and deliver it to the rotating journal, each of the strips being capable of removal from con-

tact with the journal without disturbing the others, thereby to regulate the place and quantity of oil delivery and facilitating inspection of the journal while rotating. 10

In testimony whereof I affix my signature.

CHARLES G. CUSHMAN.
